UNITED STATES PATENT OFFICE.

FRANK J. HERRICK, OF NEW BRITAIN, CONNECTICUT, ASSIGNOR TO HOWARD C. NOBLE, OF SAME PLACE.

HEEL-PROTECTOR.

SPECIFICATION forming part of Letters Patent No. 351,915, dated November 2, 1886.

Application filed April 21, 1886. Serial No. 109,595. (No model.)

To all whom it may concern:

Be it known that I, FRANK J. HERRICK, of New Britain, in the county of Hartford and State of Connecticut, have invented a certain 5 new and useful Improvement in Heel Protectors, of which the following is a description, reference being had to the accompanying drawings, where—

Figure 1 is a side view of a heel-protector embodying my improvement. Fig. 2 is a top view of the same. Fig. 3 is a view of the same in cross-section on the plane $x x$. All on enlarged scale.

This improvement is, as its name indicates, 15 a device for protecting the heel of a boot or shoe from wear.

The letter a indicates the protector proper, made of metal, preferably hardened iron or steel. It bears upon its face or top the raised 20 point b , which serves the double purpose of a frictional device, and for a time preventing the leather from coming in contact with the surface on which the boot or shoe is supported.

25 The protector a is round and peripherally corrugated, as well seen in Fig. 1. It is intended that the hole in the heel which receives this protector shall be slightly smaller in diameter than is the diameter of this protector, so that when it is forced into its seat the leather or rubber, or the like, will close 30 into the peripheral corrugations on the surface of the protector a , tending to hold it firmly in place and tending to prevent moisture from

penetrating the heel along the side surface of 35 the protector.

The letter c denotes what I will term a "nail," combined with and attached to the under face of the heel-protector, and intended to be driven into the leather or the like when 40 the protector is set to place, the idea being to make a socket, as already described, for the protector a , and in setting it to place drive the nail c into the leather beneath. It will be readily understood that this nail will have a 45 tendency to prevent the protector from escaping directly from its socket, to prevent it from being moved laterally, and especially to prevent it from being tipped or canted. The nail c is longitudinally fluted or corrugated, 50 as illustrated in Fig. 2. These flutes or corrugations on the surface of the nail c closely intermeshing, as they do, with the leather of the heel, have the tendency to prevent the protector from turning readily in its seat, and 55 they have also another important advantage, in that when driven near the edge of the heel they lessen the tendency to bulge the heel peripherally.

I claim as my improvement—
60 The round peripherally-corrugated heel-protector a , bearing on its under side the fluted nail c , substantially as described, and for the purposes set forth.

FRANK J. HERRICK.
